UNITED STATES PATENT OFFICE.

RAYMOND C. PHILLIPS, OF LOS ANGELES, CALIFORNIA, ASSIGNOR TO W. S. RUSH & COMPANY, OF LOS ANGELES, CALIFORNIA, A PARTNERSHIP CONSISTING OF W. S. RUSH, E. S. RUSH, AND B. C. GRAVES.

COUNTERSINK MACHINE.

Application filed October 6, 1924. Serial No. 741,830.

This invention relates to a machine for drilling and countersinking holes in a lining band in registration with holes in a supporting member. A specific use for which the present invention is adaptable is the boring and countersinking of holes in a brake lining in registration with the cooperating rivet holes in the brake band, or the drilling and countersinking of holes in a clutch facing. The embodiment of the invention in such a machine is described herein.

In the relining of brake bands, it is the common practice to place the lining in position on the band, then to drill and countersink holes in the lining by introducing a drill and countersink through the holes in the band so as to have proper registration. Registration of the drill with the band holes has been tedious and inconvenient. The present invention contemplates the provision of a machine having convenient registration means for guiding the drill. Registration means is provided for clutches. It is another object of this invention to provide a detail of structure, whereby the proper registration means for a particular kind of work may be presented in operating position without interference. In addition to the broader objects of this invention, there are certain details of structure and design whereby, a simple, durable, easily operated mechanism is obtained.

These objects together with other objects and corresponding accomplishments are obtained by means of the embodiment of my invention illustrated in the accompanying drawing, in which:

Fig. 1 is a side elevation of a complete machine; Fig. 2 is a plan view of the machine; Fig. 3 is a face view of the machine on an enlarged scale; and Fig. 4 is a fragmentary view similar to Fig. 1 showing the registration means in another position.

Referring more particularly to the drawing, 5 indicates a supporting frame having an upright portion 6 to which an electric motor 7 is secured. The motor is mounted in a position such that the shaft is vertical and extends through bearings in the base of frame 5. The base has an open space so that an upper table is provided and room below it for the gearing, belts, and the like. Secured to the motor shaft is a pulley 8. A vertical shaft is journaled in the front end of the base. Fixed thereon is a pulley 9. Pulleys 8 and

9 are geared together by a belt 10. The shaft to which pulley 9 is secured has a head 11 adapted to detachably receive a countersink drill 12. It is obvious that rotation of the motor shaft will cause rotation of the drill.

A depth stop 14 has arms embracing the drill. The stop is mounted upon a post 15 slidably extending through the upper portion of the frame 5. This post is rotatably secured to a screw 16 extending through the table and provided with convenient means for being grasped by the hand. By turning the screw 16, the depth stop may be raised and lowered and the depth of the countersink varied.

Mounted upon the frame is a registration standard 17. This standard is arranged with a horizontal arm so as to overhang the countersink drill when turned to the position shown in Fig. 1. It is provided with a pin 18 rotatably extending through a frame, the pin being threaded at its lower end, and mounted upon the pin is a wing nut 19. The standard 17 rests upon an elevation 20 on the table, the elevation having indentations. The standard has teeth 21 to rest in the indentations. The standard is arranged to be turned through 180°, and the teeth resting in the indentations fix the position. Formed at the end of the horizontal arm of standard 17 is a sleeve 22 for slidably receiving a centering pin 23. When the standard is in the position shown in Fig. 1, pin 23 will be in line with the drill 12. The centering pin may be raised and lowered and held in selected position by a set screw 24. Slidably extending through the standard in a horizontal direction is the centering pin 25, arranged to be held in selected position by means of a set screw 26. The parts are so arranged that by unloosening nut 19, the standard may be turned so as to present the end of centering pin 25 above the drill or the end of centering pin 23 above the drill and then locked in position.

Suppose a brake band is to be relined. Pin 23 is adjusted to a position dependent upon the thickness of the brake band and lining and so that the brake band may be inserted above the drill and removed with convenience. A brake band and lining is indicated by dotted lines in Fig. 3. The brake band with the lining in position is placed in the machine between the drill 12 and the centering pin 23,

the band being uppermost. The band is then moved so that the hole is in line with and in registration with pin 23. The correct registration may be obtained by lifting the band 5 until the centering pin enters the hole, then dropping the band upon the drill, which is caused to bore therethrough and to countersink the hole. If a cone clutch is to be relined, thumb nut 19 is loosened and the standard 13 10 turned to the position shown in Fig. 4 then locked. In this position, the centering pin 25 extends forwardly and the centering pin 23 is out of the way. The clutch is placed in position with the end of the pin 25 in registration 15 with the hole in the clutch on the inside. The clutch is now forced downwardly, the drill boring a hole through the clutch lining and countersinking the latter. The depth adjustment for countersinking and adjustment of 20 the centering pin is made as before described.

What I claim is:

1. A machine of the class described comprising: a base; a countersink drill mounted to extend upwardly therefrom; a depth stop 25 embracing said drill and having a post for raising and lowering said stop, said post being mounted upon said base; means acting upon said post for adjustably raising and

lowering said stop; an upright centering pin standard mounted to be turned on said base 30 about a vertical axis and having an overhanging arm provided with a depending adjustable pin fixed thereto in line with said drill; a centering pin adjustably mounted on said standard and extending laterally of said 35 drill; and means to lock said standard in selected positions.

2. A machine of the class described comprising: a base; a countersink drill mounted to extend upwardly therefrom; an upright 40 centering pin standard mounted to be turned about a vertical axis on said base and having an overhanging arm provided with a sleeve; a vertically adjustable pin slidably mounted in said sleeve in line with said drill; means to lock said pin in selected position; a horizontal centering pin slidably mounted on said standard and extending laterally of said drill; means to lock said horizontal pin in selected 45 positions; and means to lock said standard in selected positions.

In witness that I claim the foregoing I have hereunto subscribed my name this 24th day of September, 1924.

RAYMOND C. PHILLIPS.
